* cited by examiner

Primary Examiner—Janice E. Seeger*Assistant Examiner*—Sydney R. Buffalow(74) *Attorney, Agent, or Firm*—Lawrence Cruz; Steven A. Garner(57) **CLAIM**

The ornamental design for a mirror, as shown and described.

DESCRIPTION

FIG. 1 is a first side view of a mirror according to the present invention, the opposite side being symmetric therewith; FIG. 2 is a second side view, rotated ninety degrees from the first side view, of the mirror of FIG. 1, the opposite side being symmetric therewith; FIG. 3 is a top view of the mirror of FIG. 1; and, FIG. 4 is a bottom view of the mirror of FIG. 1.

The broken lines identify objects that form no part of the claimed design.
